UNITED STATES PATENT OFFICE.

HURLEY H. ROBBINS, OF BROOKLYN, NEW YORK.

VELOCIPED.

1,108,789.

Specification of Letters Patent. Patented Aug. 25, 1914.

Application filed May 14, 1914. Serial No. 838,559.

To all whom it may concern:

Be it known that I, HURLEY H. ROBBINS, a citizen of the United States, residing at Brooklyn, in the county of Kings and State 5 of New York, have invented certain new and useful Improvements in Velocipedes, of which the following is a specification.

My invention relates to improvements in velocipedes and resides in the provision of a 10 device wherein the body of the velocipede is formed in the shape of a horse whereby the operator may sit upon the horse and through the medium of novel gearing means, steer or guide the velocipede as desired by pulling the reins as one would ordinarily do in driving a horse.

An important object of my invention is to provide novel means whereby by pulling the bridle the operator may readily steer or 20 guide the velocipede.

Another important object of my invention is to provide novel means whereby the operator may propel the velocipede with comfort and ease.

Another important object of my invention 25 is to provide a velocipede of the character described that is simple as to construction, reliable and efficient in operation, strong, and inexpensive to manufacture.

The above and additional objects are 30 accomplished by such means as are illustrated in the accompanying drawings, described in the following specification and then more particularly pointed out as claimed.

With reference to the drawings, wherein I 35 have illustrated the preferred embodiment of my invention as it is reduced to practice, and throughout the several views of which similar reference numerals designate corresponding parts, Figure 1 is a side elevation of my improved velocipede showing the same as it would appear when in assembled position, Fig. 2 is a longitudinal fragmentary sectional view taken through the head 40 of the horse body of the velocipede illustrated in Fig. 1 and showing in detail the means for operating the steering mechanism, Fig. 3 is a detail top plan view of the bearing plate for the steering rod, Fig. 4 is a 45 detail rear elevation of the rear supporting wheels for the body of the device showing the gearing thereon, Fig. 5 is a side elevation of a modified form of velocipede, and Fig. 6 is a rear elevation of a part of the 50 modified form shown in Fig. 5.

Referring to the drawings by characters of reference, the numeral 1 designates as an

entirety a body portion that is formed in the shape of a horse, and 2 supporting wheels that are mounted upon an axle 3 which is secured to the rear or hind legs 4 of the horse.

A steering roller or wheel 5 is rotatably journaled adjacent the forward part of the body 1, within the lower end of a tubular supporting member 6 and has secured operatively thereto a steering rod 7 that extends upwardly into the body 1 through the tubular member 6 and is bent forwardly as at 8 to extend into the head 9 of the horse 1. The body 1 is preferably formed hollow and that portion 10 of the rod 7 which extends into the head 9 is designed to be swung back and forth from side to side of the head so that the steering is provided.

The upper end of the tubular member 6 is suitably connected with an elongated bearing plate 11. The bearing plate 11 is provided with an aperture 12 adjacent each of its ends and an enlarged aperture 13 centrally of its ends. Suitable fastening means, not shown are inserted through the openings 12 and serve to secure the bearing plate 11 to the body 1.

It will be readily seen that I have provided three supporting wheels for the velocipede that are arranged to safely support the body 1 so that tipping thereof is eliminated.

As a means for propelling the velocipede, I provide a crank shaft 14 that is journaled transversely through the body 1 adjacent the center thereof. The ends of the crank shaft 14 extend outwardly from the body and are provided with pedals 15 of the usual construction. A sprocket 16 is operatively connected with the crank shaft 14. A sprocket wheel 17 is rigidly connected with the shaft 3 and operatively connected with the sprocket 16 by means of a chain 18. It will be readily seen that a person sitting upon the saddle 19 provided on the body 1 and operating the crank shaft 14, will serve to rotate the axle 3 and consequently the wheels thus providing for propulsion of the velocipede.

As a means for steering the velocipede, I provide a transverse plate 20 that is carried on the free end of the portion 10 of the rod 7 and is provided with a plurality of spaced outwardly extending pins 21. Coöoperating with the plate 20 is a movable plate 22 provided with spaced openings to receive the pins 21 and mounted within the head of the

body. Extensions 23 are carried at the ends of the plate 22 and have eyes 24 formed at their outer ends. Secured to the eyes 24 are reins 25 comprising suitable flexible elements arranged about the neck of the horse comprising the body 1. The extensions 23 are slidable through the sides of the head 9 and the plate 22 is sufficiently short to enable the portion 10 of the rod 7 to swing back and forth to provide for the steering or the turning of the wheel 5. To insure the lateral sliding movement of the plate 22 so as to provide for the steering, I provide extensions 26 on opposite sides of the head 9 and adjacent to the mouth of the head in which the plate 22 is placed. These extensions 26 are arranged at right angles to the sides of the head and have journaled in their outer ends rollers 27 that are preferably of the groove type and receive the reins 25. The rollers provide for the sliding lateral movement of the plate 22 as will be clearly seen with reference to Fig. 2 in the drawings.

It will be readily seen that the operator 25 may sit upon the seat 19 and by pulling the reins 25 as one would do in guiding or driving a horse, the steering may be effected as desired.

With reference to Figs. 5 and 6 wherein I 30 have illustrated a modified form of velocipede, the wheels 2 in the preferred form are dispensed with and suitable rollers 28 are secured to the lower ends of the rear or hind legs of the horse or body portion 1. In this 35 form the steering apparatus is identical with that of the preferred form with the exception that the reins 29 are extended so that a person may sit within a small vehicle or cart 30 that is to be attached to the body portion 40 and steer or guide the device. The cart 30 is provided with propelling mechanism designated 31 as an entirety that is similar to the mechanism employed in the preferred form. The cart is provided at the rear end 45 with a pair of wheels 32, and at its forward end with preferably a single supporting wheel 33. Shafts 34 are connected with the cart 30 in the usual manner and suitably connected with the body 1.

With reference to the foregoing description and accompanying drawings, it will be seen that I have provided a novel velocipede that may be operated safely by children and which may be steered or guided in a manner 55 similar to that in connection with riding or driving a horse.

In practice, I have found that the form of my invention, illustrated in the drawings and referred to in the above description, as 60 the preferred embodiment, is the most efficient and practical; yet realizing that the conditions concurrent with the adoption of my device will necessarily vary, I desire to

emphasize the fact that various minor changes in details of construction, proportion and arrangement of parts may be resorted to, when required, without sacrificing any of the advantages of my invention, as set forth.

What is claimed is:

1. A velocipede comprising a body portion, wheels supporting the body portion, and means to steer or guide the velocipede comprising a steering rod operatively connected with one of the wheels, a plate 75 slidably laterally in the body portion, flexible elements connected with the ends of the plate, means to connect the plate with the steering rod and guides for the flexible elements projecting laterally from the body. 80

2. A velocipede comprising a body formed in the nature of a horse, wheels supporting the body and means to steer or guide the velocipede comprising a steering rod operatively connected with one of the wheels and 85 extending upwardly into the body of the horse and in the head thereof, said body being hollow, that portion of the steering rod which extends into the head being arranged to swing back and forth, means 90 slidable within the head of the horse whereby the steering rod is moved back and forth, and means to move said slidables.

3. A velocipede comprising a body formed in the nature of a horse, wheels supporting 95 the body, a steering rod operatively connected with one of the wheels and extending upwardly into the body and having its free end disposed within the head of the horse, said body being hollow, a plate having 10 a plurality of openings therein slidable within the head of the horse, said plate being slidable in a horizontal plane, flexible elements mounted on opposite sides of the head of the horse and operatively connected with 10 the ends of the plate, extensions extending at right angles to the sides of the head, rollers journaled in the ends of the extensions, said flexible elements being mounted on the rollers, said rollers being positioned beyond the 11 outer ends of the plate, a plate arranged transversely of and secured to the steering rod at the free end thereof, and a plurality of spaced pins carried by said plate and being positioned within the apertures in the 11 first named plate, said flexible elements to be pulled to slide the first named plate whereby the turning of the wheel to which the steering rod is connected, is provided.

In testimony whereof I affix my signature 12 in presence of two witnesses.

HURLEY H. ROBBINS.
